UNITED STATES PATENT OFFICE

148,237

DESIGN FOR A PIPE

Philip S. Harper, Chicago, Ill., assignor to Harper-Wyman Company, Chicago, Ill., a corporation of Illinois

Application May 4, 1946, Serial No. 129,321

Term of patent 14 years

(Cl. D85—8)

To all whom it may concern:

Be it known that I, Philip S. Harper, a citizen of the United States, residing at Chicago, in the county of Cook and State of Illinois, have invented a new, original, and ornamental Design for a Pipe, of which the following is a specification, reference being had to the accompanying drawing, forming part thereof. The pipe stem and pipe bowl are individually disclosed and claimed in applicant's copending applications, Serial Nos. D. 135,523 and D. 135,524, filed December 14, 1946.

Fig. 1 is a side elevational view of a pipe embodying my new design;

Fig. 2 is a top plan view of the pipe;

Fig. 3 is an end view of the pipe; and

Fig. 4 is a vertical cross sectional view taken along the line 4—4 of Fig. 1.

I claim:

The ornamental design for a pipe, as shown.

PHILIP S. HARPER.
